(57) **CLAIM**

The ornamental design for shears, as shown and described.

DESCRIPTION

FIG. 1 is a perspective view of shears showing my new design;

FIG. 2 is a left side elevational view showing the design for the shears of FIG. 1;

FIG. 3 is a right side elevational view showing the design for the shears of FIG. 1;

FIG. 4 is a front elevational view showing the design for the shears of FIG. 1;

FIG. 5 is a rear elevational view showing the design for the shears of FIG. 1;

FIG. 6 is a top elevational view showing the design for the shears of FIG. 1; and,

FIG. 7 is a bottom elevational view showing the design for the shears of FIG. 1.

The broken line showing of portions of the shears is included for the purpose of showing boundaries and forms no part of the claimed design.
